UNITED STATES PATENT OFFICE.

ALBERT R. CHALKER, OF PITTSBURGH, PENNSYLVANIA, ASSIGNOR TO LOCOMOTIVE STOKER COMPANY, A CORPORATION OF PENNSYLVANIA.

LOCOMOTIVE-STOKER.

1,319,375.

Specification of Letters Patent. Patented Oct. 21, 1919.

Application filed February 24, 1919. Serial No. 278,598.

To all whom it may concern:

Be it known that I, ALBERT R. CHALKER, a citizen of the United States, and resident of Pittsburgh, county of Allegheny, and State of Pennsylvania, have invented certain new and useful Improvements in Locomotive-Stokers, of which the following is a specification, and which are illustrated in the accompanying drawings, forming a part thereof.

The invention relates to stoking mechanism especially adapted for use in connection with locomotives, and in which there is provided a feed or distributor tube which enters through a wall of the fire-box, passages around the tube being provided for the admission of air for cooling its inner end, and there being a shield plate inclosing the outer end of the tube and forming with the fire-box wall a depending air chamber.

The object of the invention is to adapt the shield plate to the fire-box walls without requiring a special construction of the latter.

The rear wall or back head of a locomotive fire-box is hollow, forming a portion of the boiler. The two plates over which it is formed are united by stay bolts located as may be necessary for strength. The outer ends of these bolts are somewhat large and project a substantial distance beyond the face of the wall and are usually inclosed within a cap.

In the application to a boiler so constructed, of a shield plate for preventing the emission of smoke or flame from the fire-box through the air ports surrounding the feed tube, it is frequently found that the heads of some of the stay bolts, one or more, are in the way of the flange of the plate. This invention consists in a stoker mechanism of the type referred to having a shield plate surrounding and depending from the feed tube, and spaced apart but secured to the back head of the boiler, and a flange fitting between the plate and the back head and with these parts inclosing an air chamber, such flange being of pliable sheet metal in order that it may be bent to a proper configuration to escape the heads of stay bolts which may lie within the line which it would normally occupy.

The invention is illustrated in the accompanying drawings, in which—

Figure 1 shows a detail elevation, partly in section, of the back head of a locomotive

boiler with the shield plate and feed tube in position, the flange associated with the shield being indicated in dotted lines;

Fig. 2 is a vertical sectional view of the back head and of the fuel delivering portion of the stoker mechanism to which the feed tube is attached, the shield plate being shown in side elevation; and

Fig. 3 is a sectional detail of the shield plate on the line 3—3 of Fig. 1.

The back head of the locomotive boiler comprises the outer plate 10 and the inner plate 11, the two plates being connected, as by means of stay bolts 12, only one of which is shown. The feed tube through which fuel is discharged into the fire-box of the locomotive is shown at 13 and sets loosely through a suitable aperture in the back head, leaving spaces or ports, as 14, 15, for the admission of air for keeping the inner end of the tube cool.

This feed or distributor tube is secured to a part 16 of the fuel delivering mechanism by means of a hook bolt 17. A shield plate 18 fits upon the outer end of the tube 13, and extends a considerable distance below the same. This plate is spaced apart from the back head wall 10 to form therewith an air chamber, the sides and top of which are closed by a plate 19. This latter plate is of pliable sheet metal and is bent to the proper configuration when the parts are assembled. Preferably, as shown, it is held in place by being clamped between the plate 18 and the wall 10, and is prevented from lateral displacement by means of an instanding bead 20 on the inner face of the plate 18. This last-named plate is provided with an outstanding flange 21, through which holes may be drilled for accommodating bolts, as 22, 23, for securing it to the wall 10.

When, in properly positioning the shield plate, it is found that the normal line of the plate 19 will encounter the head of a stay bolt, as 12, it may be bowed inwardly to escape such bolt head, as indicated in dotted lines at 24. As many of these bends or distortions of the plate 19 as may be found necessary can readily be formed without detriment to the shield as a whole.

Air induction ports are provided at the lower end of the shield. In the construction shown one such port 25 is in the form of a slot across the lower end of the plate 18, and another such port 26 is provided at

the bottom by omitting a part of the wall plate 19.

There is a constant flow of air into the fire-box through the ports 25, 26, and passages 14, 15, due not only to the stack draft but to the difference in pressure between the external air and the vapors within the fire-box and the natural tendency of the air to rise in the chamber inclosed by the shield plate.

I claim as my invention—

1. The combination with a fire-box and a feed tube extending through a wall of the box, of a shield comprising an apertured plate fitting upon and depending from the tube and being spaced apart from and secured to the fire-box wall, and a plate of pliable sheet metal interposed edgewise between the plate and wall and with such elements inclosing an air chamber open at the bottom.

2. The combination with a fire-box having a studded apertured wall, and a feed tube extending through the aperture, of a shield comprising an apertured plate fitting upon and depending from the tube and being spaced apart from and secured to the fire-box wall and having an instanding bead on its inner face adjacent its margins, and a plate of pliable sheet metal interposed between the plate and wall. 25 30

3. The combination with a fire-box having an apertured wall and a feed tube fitting loosely through the aperture, of a chambered shield fitting upon the outer end of the tube and depending therefrom, and having an air port at its lower end, the marginal walls of the shield being formed of a strip of pliable sheet metal interposed between the front wall of the shield and the fire-box wall. 35

ALBERT R. CHALKER.
